DESIGN FOR A SCARF

Arthur M. Lowenthal, Rochester, N. Y., assignor to Max Lowenthal & Sons, Rochester, N. Y., a copartnership composed of Arthur M. Lowenthal and Eugene M. Lowenthal

Application November 10, 1937, Serial No. 72,758

Term of patent 7 years

To all whom it may concern:

Be it known that I, Arthur M. Lowenthal, a citizen of the United States, residing at Rochester, in the county of Monroe and State of New York, have invented a new, original, and ornamental Design for a Scarf, of which the following is a specification, reference being had to the accompanying drawing, forming part thereof.

Figs. 1 and 2 are front views, partly in perspective, of a scarf, showing my new design, with the scarf front shown open in Fig. 1 and closed in Fig. 2; and Fig. 3 is a rear view, partly in perspective, of the scarf shown in Fig. 2.

I claim:

The ornamental design for a scarf, as shown.
ARTHUR M. LOWENTHAL.
